FORMATION TESTER

George W. Rusler, Penn Township, Allegheny County, and Victor V. Vacquier, Oakmont, Pa., assignors to Gulf Research & Development Company, Pittsburgh, Pa., a corporation of Delaware

Application January 17, 1940, Serial No. 314 324

10 Claims. (Cl. 166—1)

This invention or discovery relates to formation testers; and it comprises, in apparatus for testing fluid production in wells, the combination of a string of tubing adapted for communication with the well at some level thereof and to receive fluids from the well, at least one hydraulically expandible packer surrounding the tubing and adapted to engage the well or casing walls, means for applying pressure from said tubing to the packer to expand it against the walls, means for limiting said applied pressure to a safe value and means operable from the top of the well for releasing pressure on the packer at will; all as more fully hereinafter set forth and as claimed.

5 In drilling oil and gas wells and in operating completed wells it is sometimes desirable to test certain rock formations to determine what fluids (gas, oil or water) they are producing and to determine the rate of production. The usual procedure is to lower into the well a string of tubing having a packer at its lower end, that is a device which can be mechanically expanded against the well wall to seal the upper part of the well from the lower. Sometimes a string of drill pipe is 10 used in lieu of tubing; hereinafter tubing refers to both tubing proper and to drill pipe. When the packer is expanded hydraulic connection between the inlet of the tubing pipe and the rock strata above the packer are cut off. Whatever fluid may be produced through the tubing is 15 known to come from levels below that at which the packer is set. A swab or bailer is run in and operated to withdraw any fluid entering the tubing, for study and measurement.

30

35 In ordinary formation testing apparatus, the bottom of the packer is connected to a length of pipe called the anchor. When the assemblage of tubing, packer and anchor is lowered until the anchor reaches the bottom of the well, the packer is expanded by the full weight of the tubing string applied thereto.

One disadvantage of such formation testers is that once the packer is set it is impossible to reset it at a different depth without pulling the entire string of tubing and fitting a new anchor of different length. In many cases a new packer rubber has to be used for each setting because often when a packer is pulled it is damaged. The great weight of the tubing string forces the packer against the rock with a pressure sufficient to cause the rubber to adhere tenaciously to the rock. Furthermore, pulling a packer frequently scars the walls of the hole so badly that it may be impossible to set a packer a second time at the same depth. Incidentally, in pulling a

packer from very deep wells, the tubing is subjected to a considerable overload; a load sometimes sufficient to part the tubing.

Proposals have been made to provide formation testers with hydraulically expandable packers arranged to avoid some of the disadvantages of the conventional apparatus, but in general these devices have suffered from undue complication and from the necessity of providing an additional string of tubing; an operation to be avoided if possible. 5 10

Among the objects of the present invention is the provision of a formation tester adapted to be set and removed at one or more levels in a well without the necessity of withdrawing the apparatus from the well. Another object is the provision of a formation tester including a packer so arranged that the packer is expanded under fluid pressure applied through the tubing string, and means are provided for limiting the applied pressure to a safe value, so that the packer does not adhere to the well walls. Another object is the provision of a formation tester with a hydraulically expansible packer arranged in conjunction with an air cushion device so that the packer can accommodate itself to giving away of the formation rock. Another object is the provision of a formation tester adapted for testing wells under pump operation and arranged for setting at any desired level in a well. 15 20 25 30

In the accompanying drawings are shown more or less diagrammatically three examples of specific embodiments of apparatus within the purview of the invention. In the drawings:

Fig. 1 is a view in elevation of one form of the apparatus installed in a well. 35

Fig. 2 is an enlarged sectional view, with some parts in elevation, of a modification of the apparatus of Fig. 1, fitted with a single packer.

Fig. 3 and Fig. 4 are enlarged fragmentary sectional views, with some parts shown in elevation, of a modified form of apparatus, 40

Fig. 5 is a view in elevation of the complete apparatus of Figs. 3 and 4, and

Fig. 6 is a fragmentary sectional view taken 45 along line 6-6 of Fig. 2.

Referring to the drawings and in particular to Figs. 1 and 2, the apparatus is shown (Fig. 1) as installed in a well 10 shown as uncased though it may be cased, assumed to have a fluid-producing formation 11. A string of tubing 12 extends downward from the surface, and carries at its lower end a fluid-tight cylinder or housing 13 and two packers 14 and 114 of similar construction. Each packer includes an expandible "bal-

loon" or sleeve 15 of heavy rubber hose having upper and lower canvas-reinforced rings 16 and 17 (ring 17 shows in Fig. 4) retained by flanged annular portions 18 and 19 at opposite ends of 5 a spool 20, perforated at 21 (Fig. 4). The packers can be as long as is desired and are sometimes several feet long.

A pipe 25 is threadedly attached to the bottom closure 29 of cylinder 13 at 26, and extends 10 through the upper packer. A similar pipe 125 extends through the lower packer, the lower end of the test pipe being capped at 27. Pipes 25 and 125 are joined by a length of pipe 34, having an orifice 28 between the two packers to receive well fluids. The upper packer is retained to the bottom closure 29 by a screw collar 30 on pipe 25.

Cylinder 13 encloses the operating and control mechanism for setting and releasing the packers.

20 A plate 145 forming the upper closure of cylinder 13, carries an inner cylinder 146 ported at 147 and in threaded engagement at the lower end with valve body member 148. A middle sleeve 149 joined to the lower end of tubing 12 through a coupling 150 fits snugly but rotatably within cylinder 146 and is retained against upward movement by a shoulder 151 engaging a recess 152 in the cylinder 146. Downward longitudinal movement of the middle cylinder is restrained by the body member 148. Rotation of middle sleeve 149 with respect to element 146 is restrained to a definite angular range by the provision of an arcuate slot 153 on the periphery of the shoulder 151 of sleeve 149 and stop screw 35 154 carried by cylinder 146 and projecting into the slot (Fig. 6). A port 155 is provided in middle cylinder 149 and is so located with respect to slot 153 as to register with port 147 when pin 154 is at one end of the slot and to be completely 40 out of register with port 147 when the middle cylinder is rotated to bring pin 154 into contact with the other end of the slot. An inner sleeve member 156 forms a close sliding fit within the middle sleeve 149 and is restrained from rotation with respect thereto by key-way 157 and key 158. A port 160 is provided in the inner sleeve to register with ports 147 and 155 when the inner sleeve is in its uppermost position in contact 45 with coupling 150, as shown in Fig. 2. Inner sleeve 156 is normally maintained in its uppermost position by the action of a spring 161 between body member 148 and base 162 of the inner sleeve. A short tube 163 advantageously integral with base 162, projects upwardly inside the inner sleeve to a level above port 160 and its bore, providing fluid communication from a point above the level of port 160 to the opposite side of base 162. The valve body 148 carries a 50 plunger 164 loaded with a spring 165 projecting upwardly out of the valve body and adapted, when struck by tube 163, to depress a lever 166 which is pivoted on a support 166 and operatively connected to a smaller spring-loaded plunger 65 167. Plunger head 168 fits in valve cage 169 and in its uppermost position is adapted to hold a ball 170 against the opening of a duct 171. Depression of plunger 167 releases the ball and places duct 171 in communication with a duct 70 172 leading to the exterior of the casing through a tube 173. Duct 171 is in communication with the interior of the packer through a ball valve recess 174, passageway 175, pipes 176 and 177 and a passageway 178. Ducts 171 and 175 communicate with the interior of tubing 12 through 75

a bore 179 normally closed by a spring-pressed ball valve 192.

A pneumatic vessel 181 is joined to valve body 36 and includes a cylinder head 182 and bottom closure 183 with a free sliding piston 184 interposed therebetween. Air may be injected into the chamber between the cylinder head and piston through check valve 185 and conduit 186 normally closed by plug 187 in plate 145 of cylinder 13. The chamber between closure 183 and 10 the piston is in communication with pipe 177, as shown, through a frustoconical seat 188 accommodating an extension 189 of similar shape on the lower extremity of the piston 184. Communication between pipe 25 and the tubing 12 15 is afforded through a plurality of openings 190 in plate 29.

In operation, before the packer is introduced into the well the coupling 150 is turned as with a wrench to place port 155 out of register with port 147, thus preventing any fluid in the well from flowing through the mechanism during descent. Plug 187 is removed and air or other gas introduced into vessel 181 through valve 185 under a pressure somewhat less than the formation pressure to be expected at the level to be tested. Such pressure may vary from a few pounds to several thousand pounds per square inch. Sufficient oil (not shown) is introduced to fill the packers without expanding them and to 20 fill pipe 176. Under these conditions piston 184 rests on closure 183, under air pressure. The apparatus is then lowered to the desired level. On reaching the position at which the packer is 25 to be set, the tubing 12 is filled with oil and pressure is applied by pump 61, which is transmitted through tube 163 and passageway 179 and forces valve ball 192 away from its seat, thus placing the inside of the packer under the pressure of the oil in the tubing through pipes 176 and 177 30 and passageway 178, and at the same time placing the lower side of piston 184 under the pressure of the oil in the tubing through pipe 177. 35

As the pressure increases oil flows through pipe 176 to the interior of the packers and to 40 the lower part of vessel 181. The packers are expanded against the well walls, making a tight seal. The pressure, read at gage 62, is kept low enough to avoid adhesion of the packer rubbers to the rock. If the well contains liquid above 45 the packer assemblage the height of the liquid column is allowed for in determining the differential pressure to be maintained on the packers. This application of pressure simultaneously forces piston 184 upwardly in the air cylinder 50 against the pressure of the compressible gas therein. Should the formation give way a little, as sometimes happens after the packer is set, some of the reserve oil below the piston will flow 55 into the packers and expand them, thus preserving the seal. The pneumatic vessel 181 and piston 184 thus make up an accumulator.

With the packer set, tubing 12 is rotated so as to place port 155 in register with ports 147 and 160 whereupon a swab or bailer (not shown) 65 is run in the tubing in a known way to test production. Assuming the apparatus to be opposite a producing formation (Fig. 1) well fluids will flow in through port 28, pipe 25, ports 190, 147, 155 and 160. In some cases the formation pressure is sufficient to cause formation liquids to rise to the top of the well, in which case no continued swabbing or bailing is necessary.

If it is desired to move the packer to a lower position in the well, tubing 12 is first rotated 70

so as to place ports 147 and 155 out of register, and then a messenger 194 is lowered on a wire line 195 until it strikes tube 163 depressing sleeve 156 against the action of spring 161 until plunger 164 is depressed against its spring causing lever 165 to depress plunger head 168. Valve ball 170 then falls from its seat placing vent pipe 173 in communication with the inside of the packers through ducts 172 and 175 and pipe 176. The pressure in the packers is thus relieved and the packers deflated. The messenger is then withdrawn whereupon the sleeve 156 and the plunger 164 return to their original uppermost positions, and ball 170 is forced against its seat. The mechanism is then lowered to the new position whereupon the operations previously described for inflating the packers are repeated. If desired, the strengths of the springs associated with valve 170 and plunger 164 may be so adjusted as to limit the pressure attainable in the packer, whereupon valve 170 acts as a relief valve. Of course, the springs should be made strong enough to keep the valve closed within the range of pressures that will be encountered in a given well.

When it is desired, after having once set the packer, to remove it to a higher position, or to remove the apparatus from the well, different technique is employed to avoid a "wet job" in pulling the tubing string. Tubing 12 is not rotated as before, but ports 147 and 155 are left in register. The messenger is lowered to release exhaust valve 170, thereby deflating the packers. In so doing, tubing 12 is temporarily placed out of communication with pipe 25 because port 160 is out of register with ports 147 and 155, and hence the tubing fluid cannot be emptied until the deflation of the packers is completed. After deflation of the packers, the messenger is removed, whereupon the sleeve 156 again rises to its original position placing ports 147, 155 and 160 in register and allowing the tubing to drain into the well through passages 190 and pipe 25. When the higher position is reached at which it is desired to set the packer, the messenger is again lowered sufficiently to depress sleeve 156 by an amount sufficient to place port 160 out of register with ports 147 and 155, but not sufficient to cause depression of plunger 164. With communication between the tubing and the formation thus closed off, oil pressure may again be applied to the packer interiors and the vessel 181. After the packers are set the messenger is again removed and the formation produced as before, port 160 again being in register with ports 147 and 155. The portion of the apparatus between the upper side of valve body 148 and closure 145 need not be constructed to the vertical scale shown in the drawings but if desired can be made relatively longer, to afford greater latitude in positioning the sleeve 156 so that port 160 is out of register with ports 147 and 155 while the lower end of tube 163 does not come in contact with plunger 164. The range of travel of sleeve 156 may be several feet if necessary.

If it is desired merely to test for production below a certain single level, as in bottom-hole testing, instead of testing for production between two levels, the lower packer 114 and its fluid connection 59 are simply omitted, and coupling 64 for tube 59 is replaced by a plug (not shown).

It is often desirable to test fluid producing formations under conditions of steady pumping. On the average, pumping wells produce about 4 barrels of water for each barrel of oil. In many

wells it is possible to take steps to reduce the water-oil ratio if the depth at which water enters the well can be accurately determined.

Figs. 3, 4 and 5 show a modification of the invention adapted for testing formations under pumping conditions. Fig. 4 is a continuation of Fig. 3; point X on Fig. 4 corresponds to point X on Fig. 3.

The apparatus includes a pump, of conventional construction per se, including a working barrel 112, a detachable standing valve 70 in the lower portion of the barrel, and a conventional valved piston 71 adapted to be reciprocated from the surface by a rod 72. A catch 68 extending below the piston is provided, adapted to engage a post 69 on the standing valve for pulling the standing valve when desired. Two packers 214 and 314 are provided of construction quite similar to packers 14 and 114 of Fig. 1. Working barrel 112 is adapted to be attached directly to the string of tubing 12 and is of smaller diameter than the tubing as shown in Fig. 5. In a pumping well, the lower extremity of the tubing reciprocates through a range of a foot or two due to the loading and unloading of the tubing as the pump piston intermittently picks up the load of the fluid column on the upstrokes. Since the packers when once set remain stationary in the well, it is necessary to make some provision for a relative movement between the packer assembly and the working barrel or tubing. In the specific embodiment illustrated in Fig. 3, this is accomplished as follows: There is provided an annular member 74 surrounding the pump barrel 112 and carrying packing 75 to make a snug sliding fit with the barrel. Member 74 carries a protective casing 73 enclosing the working parts of the packer controlling mechanism, which casing is closed at the bottom by closure member 76. Guide sleeve 77 is disposed concentrically with respect to the barrel 112 and is carried in threaded engagement with element 74 as at 78. A threaded closure ring 80 engages a pipe nipple 81, which in turn engages the central bore 82 in closure 76, thus affording communication through the ring 80 and closure 76 between the inlet 86 of the standing valve 70 and the pipe 88 carrying well fluids through the packers. A member 83 is attached to the lower end of barrel 112 and forms a seat for standing valve 70. Member 83 carries packing 85 and packing ring 130 which together with the member 83 form a fluid-tight, sliding fit with sleeve 71. Thus, the working barrel 112 and pump piston 71 are each free to reciprocate with respect to element 74 and its associated parts. In order to permit hanging the packer assembly on the tubing when lowering into the well without interfering with communication between the interior of the tubing and port 108, element 83 is provided with a lip A at its upper extremity thus affording an annular space between the element 83 and the outer wall of barrel 112. A lip B is likewise provided on the lower extremity of member 74 and is so arranged as to contact lip A of the working barrel when the packer assembly is hung on the barrel. Lip B projects downwardly between sleeve 71 and barrel 112 with clearance on both sides, and a port 131 provides communication between the annulus on each side of the lip B.

Each packer comprises a rubber hose 15 attached to a spool 20. A pipe 88 threadedly attached to member 76 extends through the upper packer as shown (Fig. 4). The upper packer 75

is retained against member 76 by a threaded ring 89 engaging the annular closure 90 of the packer. Packing 200 is arranged between closure 90 and a ring 201 welded to pipe 88, as shown. 5 Pipe 88 is coupled by a coupling 91 with a lower pipe 92 extending through and carrying the lower packer. Supporting ring 202 is welded to pipe 92 and lower packer 214 is held thereagainst by a head 490 and a threaded ring 95 10 engaging threads on pipe 92. The joint between head 490 and pipe 92 is sealed by packing 96 held by gland 93 and ring 198 which is welded to pipe 92 at 94. Between gland 93 and ring 198 a suitable number of washes 199 is disposed to adjust 15 the tightness of the packing in conformity with the overall length of the packer. A similar gland and adjusting washes are provided between ring 201 and closure 90 of the upper packer 214. The two packers are joined by a tube 59 as in Figs. 20 1 and 2.

The lower pipe 92 carries an inner pipe 98 in telescopic sliding relation therewith and having a flanged cap 99 at the bottom. Pipe 98 has a stop 100 sliding in a slot 101 in pipe 92, to restrain motion of pipe 98 to a fixed range. Pipe 98 has a port 102 adapted to register with a port 103 in pipe 92 in the upper position of pipe 98. A coil spring 104 urges pipe 98 downward, with a force sufficient to prevent upward movement of the pipe under any formation pressures encountered. The length and limits of movement of pipe 98 are such that when extended downwardly to its lowermost position port 105 in pipe 92 is open and port 103 in pipe 92 is 30 closed. When pipe 98 is moved upwardly to its uppermost position port 105 is closed and port 103 opened through registry with port 102 in pipe 98.

In the apparatus of Figs. 3, 4 and 5, the packers 40 are expanded under pump pressure, which pressure is kept to a safe value. As shown, the pump working barrel is ported at 106 and at 107 and the guide cylinder 77 is ported at 108. Port 108 communicates through an elbow fitting 109 45 and a tube 110 and a duct 113 in valve cage 111; a plunger valve 142 being interposed in the duct. Duct 113 communicates through chamber 144 and duct 115 with the interior of the upper packer 214. Thus, as pressure is built up in 50 tubing 112 above the standing valve 70, liquid is forced into the packers, expanding them against the well walls.

Valve 142 has a plunger 118 which is surrounded by a flexible metallic bellows 119 and urged downwardly by a spring 120, arranged as shown. The interior of the bellows is vented to the interior of the well by a duct 205 and a port 204 in the casing 73. Upon development of excessive pressure in the packers and in chamber 55 144, the pressure in chamber 144 acting on the bellows closes the ball valve so that no more pressure fluid reaches the packers.

The lower closure 80 of the guide sleeve is 60 fitted with a ball valve 121 in a cage 122 which is connected through a tube 124 and a duct 225 in member 76 with the interior of the packers. The valve ball is normally urged upward by a spring 126 as well as by fluid pressure in the packers. A pin 127 urged upward by a spring 70 70 75 128 is so arranged that by lowering the pump assembly to its lowermost position, the pin is depressed to open the ball valve and thereby release pressure on the packers through a duct 123 which connects valve cage 122 with the in-

terior of casing 73 and hence with the well fluid through port 204.

The operation of the apparatus of Figs. 3, 4 and 5 is as follows: As the apparatus is being lowered into the well, the packer assemblage hangs in its lowermost position with respect to the pump, that is with the lip A of the pump closure 83 resting against the lip B of closure 74. The packers are in collapsed condition. When the apparatus reaches the desired level, the pump is put into 10 operation. As the pump operates the liquid column rises in the tubing string thus causing an increase in pressure in the pump barrel (space 206) which is communicated to the packers through ports 106 and 108, tube 110, duct 113, chamber 144 and duct 115. When the packers grip the walls of the well sufficiently to support the weight of the packer assembly, then the pump barrel 112 will reciprocate downwardly from its initial position (with parts A and B in contact) as the load on the tubing due to the rising fluid column is increased. Soon the relative pressure between the pump chamber and the fluid column in the well above the packers reaches the predetermined shutoff valve for which valve 142 is set, whereupon the valve closes as described and the packer is locked in its expanded condition. Should any leakage take place in the packer system, reducing pressure therein, valve 142 automatically opens. During the test the 30 assemblage of the two packers and the attached casing 73 remains stationary, while the pump barrel 112 reciprocates with respect to the packer assembly and the pump piston reciprocates with respect to the barrel 112 and the packer assemblage.

Thus the packer is automatically set simply by starting up and operating the pump, and the reciprocation of the tubing string is accommodated without straining the packing assembly. 40

In order to release the packer, the standing valve 70 is pulled out of working barrel 112 into the larger diameter tubing 12 whereupon the fluid column in tubing 12 escapes around plunger 71 and valve 70 into the well, then the tubing string is simply lowered until member 130 depresses pin 127 and opens exhaust valve 121.

This establishes hydraulic connection between the packer interior and the well fluid through ports 123 and 204, whence there is considerable 50 relief of the pressure inside the packer, in consequence of which the packer will no longer sustain the weight of the packer assembly which moves downward in the well, permitting relief valve 121 to close. As the packers are not entirely deflated when valve 121 closes, there is still some mechanical drag, and this is overcome as follows: The partial relief of pressure inside the packers afforded by opening the relief valve 121 is sufficient to cause valve 142 to open under the influence of spring 120, and hydraulic connection between the packers and the well is thus established through ports 106 and 107 and opening 86. The pressure within the packers is thus entirely relieved and the disengagement of the packer from the walls of the well is complete. 60 65 70 75 80 85

The sliding tube 98 is arranged to permit tests of bottom hole pressure in addition to tests of production between fixed limits. Thus by lowering the whole apparatus to the bottom of the well until cap 99 strikes bottom, tube 98 closes port 105 and opens ports 102 and 103, thereby causing well fluids to be drawn only from below the lower packer. At levels above the bottom, spring 104 75 80 85 90 95

causes ports 102 and 103 to be shut off and port 105 to be open as shown in Fig. 4.

The apparatus of Figs. 3 to 5 can, of course, be employed as a single packer formation tester 5 by simply omitting coupling 91 and all parts below it.

The apparatus is embodied in the usual materials for oil well apparatus such as steel and bronze.

10 What we claim is:

1. A formation tester for wells comprising in combination a string of tubing extending down the well, a hollow hydraulically expansible packer adjacent the lower end of the tubing, a sampling 15 pipe in communication with the tubing, extending through the packer to a portion of the well below the packer, valve means for said pipe closable to prevent flow of liquid therethrough while the packer is being lowered, operable from the top 20 of the well, a duct leading from the tubing to the interior of the packer, check valve means in said duct opening toward the packer, whereby upon development of pressure in the tubing the packer is expanded and pressure in the packer is held by 25 the check valve, and packer vent means operable from the top of the well for venting the interior of the packer to the well.

2. A formation tester for wells comprising in combination a string of tubing extending down 30 the well, a hollow hydraulically expansible packer adjacent the lower end of the tubing, a sampling pipe in communication with the tubing and extending through the packer to the well space below the packer, valve means for said pipe closable 35 to prevent flow of liquid therethrough while the packer is being lowered, operable from the top of the well, a duct leading from the tubing to the interior of the packer, check valve means in said duct opening toward the packer, whereby upon 40 development of pressure in the tubing the packer is expanded and pressure therein is held by the check valve, pressure-limiting means in communication with the packer and adapted to limit pressure in the packer to a predetermined moderate 45 value, and packer vent means operable from the top of the well for venting the interior of the packer to the well.

3. In a formation tester for wells including a string of tubing extending down the well, a hollow 50 hydraulically expansible packer adjacent the lower end of the tubing, a sampling pipe in communication with the tubing and extending through the packer to the well space below the packer, a duct leading from the tubing to the interior 55 of the packer for application of fluid pressure to the interior of the packer, and a check valve in said duct for holding pressure in the packer, the improvement comprising a pressure accumulator in liquid communication with the interior of the packer, adapted to retain a reserve of pressure fluid in communication with the packer, so that the packer is kept in expanded 60 condition upon caving of the well walls.

4. In combination, a string of tubing extending 65 downwardly into a well, a formation tester attached to the bottom of said tubing comprising a pair of vertically spaced hydraulically expansible packers, a fluid conduit through the interior of the upper packer connecting the tubing with a 70 well space intermediate the two packers, movable means in said conduit adapted in one position to prevent flow of fluid from the tubing to the well and in another position to permit flow thereto, mechanical means operable from the surface of the well independently of said tubing, said me-

chanical means being adapted to move said movable means from one to the other position when the packers are unset and hanging on the tubing, a fluid passageway connecting the hydraulically expansible portion of both packers with the interior of the tubing, a one-way valve in said passageway adapted to admit to the expansible portion of the packers and retain therein fluid under pressure from the tubing and mechanical means operable from the surface for venting the expandable portion of both packers to a space exterior of the tubing and the packers. 10

5. In combination, a string of tubing extending downwardly from the surface of a well, a formation tester attached to the bottom of said tubing 15 comprising a pair of vertically spaced hydraulically expansible packers, a fluid conduit connecting with the tubing and extending through the interior of both packers, movable means in said conduit adapted in one position to prevent flow of 20 fluid from the tubing to the well and in another position to permit flow thereto, mechanical means operable from the surface of the well independently of said tubing, said mechanical means being adapted to move said movable means from one 25 position to the other when the packers are unset and the tester is hanging on the tubing, a fluid passageway connecting the hydraulically expansible portion of both packers with the interior of the tubing, a one-way valve in said passageway 30 adapted to admit to the expansible portion of the packers and retain therein fluid under pressure from the tubing, mechanical means operable from the surface for venting the expansible portion of both packers to a space exterior of the tubing and 35 the packers, an opening in said conduit communicating with the well space intermediate said two packers, a second opening in said conduit communicating with the well space below the lower packer and a spring-urged member extending 40 downwardly below the lower packer and movable vertically with respect thereto, said member being adapted to open said first-named opening and close said second-named opening when extended downwardly under the urge of the spring and to 45 open said second-named opening and close said first-named opening when moved upwardly through contact with the bottom of the well on lowering the tester.

6. Apparatus for testing fluid production in 50 wells comprising a string of tubing adapted for communication with the well at some level thereof and to receive fluids therefrom, at least one hydraulically expansible packer surrounding the tubing and adapted to engage the well walls, a 55 housing in fixed relation to the packer, a pump barrel attached to the lower portion of the tubing and in reciprocable relation to the housing, a pump plunger in reciprocal relation to the pump barrel, a standing valve in said pump barrel, said 60 plunger and said standing valve defining a chamber in said barrel, conduit means connecting the pump chamber with the packer so that upon operation of the pump the packer is expanded against the well walls, relief valve means in said 65 conduit means adapted to bypass fluid from the packer when the fluid pressure rises above a predetermined value, and valve means in the housing operable by the pump barrel in one position thereof, for releasing pressure in the packer to 70 collapse the packer.

7. Apparatus for testing fluid production in wells comprising a string of tubing extending down the well, a housing attached to the tubing, a pump mounted in the housing in reciprocating 75

relation therewith, at least one hydraulically expandible packer mounted on the housing and adapted to engage the well walls, conduit means extending from below the packer to the pump for 5 passage of well fluids to the pump, conduit means connecting the pump chamber with the packer for expansion of the packer by pump pressure, valve means in said conduit means adapted to close said conduit means upon development of a 10 predetermined pressure in the packer, and means operable by the pump when in its lower position, for releasing pressure in the packer to collapse the packer.

8. An apparatus for testing fluid production in 15 wells comprising a string of tubing, at least one hydraulically expandible packer adapted to seal the space between the tubing and the well walls, a chambered housing attached to the tubing and communicating with the well below the packer, 20 an outer sleeve within the housing and fixed to the housing, a bottom closure for said sleeve within the housing, an intermediate sleeve within the outer sleeve and in fixed relation to the tubing, means for restraining movement of the 25 intermediate sleeve with respect to the outer sleeve to rotary movement, an inner sleeve within the intermediate sleeve, means for restraining movement of the inner sleeve with respect to the intermediate sleeve to a vertical sliding movement, a perforate bottom closure for the inner 30 sleeve, said three sleeves having orifices adapted to register in one relative position of the three sleeves whereby to establish communication for well fluids between the interior of the housing 35 and tubing, and adapted to be put out of register by rotating the intermediate sleeve, to close the tubing while the apparatus is being lowered in the well, and also to be put out of register by depressing the inner sleeve, to close the tubing 40 while the packer is being reset, conduit means 45 leading from the interior of the packer and having a vent branch delivering outside the housing and a supply branch delivering through said closure for the outer sleeve to the space between said closure and said perforate closure of the inner sleeve, a check valve in said supply branch, a valve in the vent branch and operating means for the vent valve so constructed and arranged

that upon depression of the inner sleeve said valve is opened to vent the packer.

9. A well testing apparatus comprising in combination a string of tubing extending down the well, a housing attached to the lower end of the tubing, a hydraulically expandible packer attached to the housing, a sampling tube in communication with the tubing and extending through the packer into communication with the well below the packer, a guide sleeve within the 10 housing in fixed relation thereto and provided with a base, an inner sleeve in telescopic sliding relation to the guide sleeve and constructed and arranged normally to remain above and away from the base, a conduit connection between the 15 tubing and the interior of the packer, a valve in said conduit connection permitting flow of liquid from the tubing to the packer for expansion thereof, a vent duct delivering from the interior of the packer to a point outside the tubing, normally closed valve means in said vent duct, and opening means for said valve means extending up through the sleeve base and adapted for operation by said inner sleeve when moved down below its normal position toward said sleeve base. 25

10. A well formation tester comprising a string of tubing extending down the well, a hollow sleeve type hydraulically expandible packer carried at the lower end of the tubing, a fluid conduit extending from the tubing through the 30 packer to a portion of the well therebelow, movable means in said conduit adapted in one position to open and in another position to close said conduit against flow of fluid from the tubing to the well, said movable means being provided 35 with an actuating element projecting into said tubing, a removable operating member adapted to be lowered through said tubing and adapted to engage and actuate said element, a duct connecting the expandible portion of the packer 40 interior with the tubing above said movable means when in the closed position, a check valve in said duct opening toward the packer interior and packer vent means operable from the top of the well for venting the interior of the packer to 45 the well.
